UNITED STATES PATENT OFFICE

THORE R. E. RUNDQVIST, OF CLAREMONT, NEW HAMPSHIRE, ASSIGNOR TO SULLIVAN MACHINERY COMPANY, A CORPORATION OF MASSACHUSETTS

FLUID-PRESSURE MOTOR

Application filed December 20, 1923. Serial No. 681,848.

My invention relates to pressure fluid motors.

An object of my invention is to provide an improved pressure fluid motor. Another object of my invention is to provide an improved motor in which extreme rapidity of reciprocation may be obtained. Still another object of my invention is to provide an improved motor of the pressure fluid percussive type especially adapted for rock drilling purposes in which by reason of increased speed and power of reciprocation, the speed of drilling is materially increased. A still further object of my invention is to provide an improved valve mechanism for motors and especially adapted for rock drilling motors of the percussive type. These and other objects and advantages of my invention will, however, hereinafter more fully appear.

In the accompanying drawings I have shown for purposes of illustration one form which my invention may assume in practice.

In these drawings,—

Fig. 1 is a central longitudinal vertical sectional view through a drilling motor in which an illustrative form of my invention is incorporated, the view being partially in side elevation.

Fig. 2 is a view similar to that shown in Fig. 1 with parts assuming different positions.

Fig. 3 is a detail side elevational view, partially in section, of a portion of my improved mechanism.

Fig. 4 is a transverse sectional view taken substantially on line 4—4 of Fig. 3.

Fig. 5 is an end elevation view of one of the buffer plugs.

Fig. 6 is a detail view of the improved valve mechanism.

In this illustrative form of my invention, I have shown a pressure fluid percussive motor, generally designated 1, comprising a cylinder 2 having a bore 3 in which a piston 4 is reciprocable. The piston 4 is provided with a projecting striking bar 5 adapted to per-

cussively actuate a drill steel (not shown) suitably carried within the front end of the motor in a well known manner. The opposite ends of the cylinder bore 2 are closed by suitable head members 6 and 7, the former being held in the desired assembled relation by means of side rods (not shown) in the usual manner while the latter is forged integral with the cylinder 2.

Pressure fluid is distributed alternately to the ends of the cylinder by means of distribution passages 8 and 9, the supply and exhaust of pressure fluid through these passages 8, 9 being controlled by a valve mechanism of improved construction, generally designated 10. Herein the valve mechanism comprises a casting or chest 11 in which suitable valve bushings 12 are so arranged as to form a valve chamber having bores 13 and 14 of different diameters. These passages 8, 9 communicate with the valve chamber adjacent the ends of the enlarged central bore 14 terminating in annular grooves 15 and 16. Adjacent the extremities of the smaller bores 13, ports 17 and 18 connect throw or reverse passages 19 and 20 with the valve chamber, these passages at their opposite ends communicating with the bore of the cylinder 2 by longitudinally spaced ports 21 and 22. Intermediate the port 17 and groove 15, and port 18 and groove 16, respectively, in the valve chest there are formed annular grooves 23 and 24, which grooves communicate by ports 25 and 26 with an exhaust passage 27 formed in a box-like member 28 suitably secured to the valve chest. As illustrated, a valve, generally designated 29, is arranged within the valve chest which is herein of the multiple spool type and comprising recessed end spools or heads 30 fitting the bores 13 and a central grooved spool or head 31 fitting the bore 14, the heads 30, 31 being connected by reduced portions 32. Herein, it will be observed that the outer ends of the bores 13 are closed by buffers or plugs 33 and 34 with which the recessed ends 30 of

45 50 55 60 65 70 75 80 85 90 95

the valve are adapted to engage and which are held in the desired assembled rigid relation by means of a bolt 35 extending coaxially through the axis of the valve. These buffers 33, 34 are laterally grooved at 36 and 37, which grooves permit the ready supply and exhaust of fluid between the ends of the buffers and the valve. Herein, the pressure fluid supply communicates with an annular space 38 formed between the ends of the valve bushings 12 in the central part of the valve chest.

In my improved construction it will be noted that the bolt 35 is traversed by a plurality of radially extending longitudinally spaced ports 39 and 40 which communicate by means of circumferentially extending grooves 41 and 42 with the bores 13 in the valve chamber at points adjacent the inner ends of the buffer plugs 33, 34. Ports 39 and 40 also communicate by way of passages 43 and 44 arranged coaxially through the ends of the bolt, with the atmosphere. Herein, formed intermediate the grooves 41 and 42 are annular grooves 45 and 46 formed in the outer periphery of the bolt 35 which are provided with longitudinally extending slots or grooves 47 and 48 extending to a point adjacent the grooves 41 and 42. The buffer plugs 33 and 34 are radially slotted or grooved as at 33' (see Fig. 5). Herein, it will further be noted that the reduced portions 32 of the valve 29 are traversed by a plurality of angularly disposed ports 49 and 50 which are alternately adapted to permit communication between the grooves 45, 46, slots 47, 48, slots 33' in the buffer, the valve chamber adjacent the inner ends of the buffers 33 and 34, and the reverse ports 19 and 20.

In the operation of my improved mechanism it will be observed that when the valve assumes the position shown in Fig. 1, pressure fluid passes from the inlet space 38 to the left of the grooved central spool 31 of the valve and by way of passage 8 to the rear end of the piston 4 to cause forward movement thereof. Simultaneously the front end of the cylinder is connected by passage 9 with exhaust. The piston 4 will accordingly move forward and during its forward movement the rear edge of the piston head uncovers the reverse port 20 admitting live pressure fluid to the right hand end of the valve, reversing the same and the hammer piston as shown in Fig. 2, the passage 9 communicating with the inlet pressure and the passage 8 with exhaust. When the valve has assumed the position shown in Fig. 2, the pressure fluid acting on the right hand side of the grooved central spool 31 forces the valve in seated position against the buffer plug 33 and when in that position the live pressure fluid is admitted through the port 49 in the valve, annular grooves 45 in the bolt, and slot 47 which registers with the

slots 33' in the buffer plug, the fluid flowing through slots 33' to the chamber at the left hand end of the valve thereby causing a pressure to build up in the reverse port and in the rear of this head of the valve substantially balancing the same. If, however, an excessive pressure builds up tending to overcome the pressure acting on the head 31, the valve will unseat slightly from the buffer thus opening communication with the grooves 41, ports 39, and opening 43 to exhaust reducing the pressure, again causing the valve to seat and eliminating the consequent excessive fluttering of the valve and preadmission of pressure fluid to the cylinder bore. These balanced pressures acting on the side of the head 31 and the rear of the head 30 and the preadmission of pressure fluid to the reverse port permit a more rapid valve action when the reverse port 21 is uncovered by the piston head, consequently increasing the power and speed of the hammer piston. It will also be noted that when the valve assumes the position shown in Fig. 1 a similar action occurs, the pressure fluid passing through the similar set of ports and grooves in the other end of the valve and bolt.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a pressure fluid motor, a cylinder, a piston reciprocable therein, means forming distribution passages leading to said cylinder, a valve controlling said passages, means forming throwing passages for admitting live pressure fluid to the ends of said valve for throwing the latter, and auxiliary means controlled by said valve for admitting live pressure fluid to one end of said valve prior to the admission of throwing pressure to said end.

2. In a pressure fluid motor, a cylinder, a piston reciprocable therein, means forming distribution passages leading to said cylinder, a valve controlling said passages, means forming throwing passages for admitting live pressure fluid to the ends of said valve for throwing the latter, auxiliary means controlled by said valve for admitting live pressure fluid to one end of said valve prior to the admission of throwing pressure to said end, and means controlled by said valve for preventing premature throwing thereof.

3. In a pressure fluid motor, a cylinder, a piston reciprocable therein, means forming distribution passages leading to said cylinder, a valve controlling said passages, means comprising throwing passages controlled by

- said piston for admitting live pressure fluid from said cylinder to the ends of said valve for throwing the latter; and auxiliary means controlled by said valve for admitting live pressure fluid to one end of said valve prior to the admission of throwing pressure to said end.
4. In a pressure fluid motor, a cylinder, a piston reciprocable therein, means forming distribution passages leading to said cylinder, a valve controlling said passages, means forming throwing passages for said valve, auxiliary means for admitting live pressure fluid to one end of said valve substantially balancing the same prior to the throwing action thereon, and means controlled by said valve for preventing a premature throwing of the latter.
5. In a pressure fluid motor, a cylinder, a piston reciprocable therein, means forming distribution passages leading to said cylinder, a valve controlling said passages, means forming throwing passages for said valve, auxiliary means for admitting live pressure fluid to one end of said valve substantially balancing the same prior to the throwing action thereon, and means including vent passages controlled by said valve for preventing a premature throwing of the latter.
6. In a pressure fluid motor, a cylinder, a piston reciprocable therein, means forming distribution passages leading to said cylinder, a valve controlling said passages, means forming throwing passages for said valve, auxiliary means controlled by said valve for admitting live pressure fluid to one end of said valve substantially balancing the same previous to the throwing action thereon, and means controlled by said valve for preventing said auxiliary means from allowing a pressure to be built up great enough to throw said valve.
7. In a pressure fluid motor, a cylinder, a piston reciprocable therein, means forming distribution passages leading to said cylinder, a valve controlling said passages, buffers limiting the movement of said valve, means for holding said buffers in assembled relation, and means disposed in said last mentioned means and controlled by said valve for admitting pressure fluid to an area on one end thereof previous to the throwing action on said area.
8. In a pressure fluid motor, a cylinder, a piston reciprocable therein, means forming distribution passages leading to said cylinder, a valve controlling said passages, means forming throwing passages for admitting live pressure fluid to opposed areas on said valve for throwing the same, buffers limiting the movement of said valve, means for holding said buffers in assembled relation, and means disposed in said last mentioned means and controlled by said valve for admitting pressure fluid to one end thereof substantially balancing the opposing pressure tending to hold said valve in position previous to the admission of throwing pressure to said end.
9. In a pressure fluid motor, a cylinder, a piston reciprocable therein, means forming distribution passages leading to said cylinder, a valve controlling said passages, buffers for limiting movement of said valve, a bolt for guiding said valve and for maintaining said buffers in assembled relation, said valve having opposed surfaces, means for alternately subjecting said surfaces to fluid pressure for throwing said valve, and means provided by said bolt for admitting live pressure fluid alternately to said surfaces to accelerate the throwing action.
10. In a pressure fluid motor, a cylinder, a piston reciprocable therein, means forming distribution passages leading to said cylinder, a valve controlling said passages, buffers for limiting movement of said valve, a center bolt for guiding said valve and for maintaining said buffers in assembled relation, said valve having opposed surfaces, means for alternately subjecting said surfaces to fluid pressure for throwing said valve, and means provided by said center bolt and controlled by said valve for admitting live pressure fluid alternately to said surfaces to accelerate the throwing action.
11. In a pressure fluid motor, a cylinder, a piston reciprocable therein, means forming distribution passages leading to said cylinder, a valve controlling said passages, means forming throwing passages for said valve, buffers for limiting movement of said valve, a center bolt for guiding said valve and maintaining said buffers in assembled relation, and means provided by said center bolt and controlled by said valve for admitting live pressure fluid to one end of the latter prior to and for accelerating the throwing action thereon.
12. In a pressure fluid motor, a cylinder, a piston reciprocable therein, means forming distribution passages leading to said cylinder, a valve controlling said passages, means forming throwing passages for said valve, buffers for limiting movement of said valve, a center bolt for guiding said valve and maintaining said buffers in assembled relation, means provided by said center bolt and controlled by said valve for admitting live pressure fluid to one end of the latter prior to the throwing action thereon, and means for venting the said end of said valve for preventing premature throwing thereof.
13. In a pressure fluid motor, a cylinder, a piston reciprocable therein, means forming distribution passages leading to said cylinder, a valve controlling said passages, means for admitting live pressure fluid to the ends of said valve for throwing the latter, buffers for limiting movement of said valve, a center bolt for guiding said valve and maintaining said buffers in assembled relation, means com-

prising passages formed in said bolt for admitting live pressure fluid to the ends of said valve and for venting the ends of the latter, and means including passages formed in said valve for alternately opening and closing said passages.

14. In a pressure fluid motor, a cylinder, a piston reciprocable therein, means forming distribution passages leading to said cylinder, a valve controlling said passages, buffers for limiting movement of said valve, a bolt extending centrally through said valve for maintaining said buffers in assembled relation, said valve having opposed surfaces, means for alternately subjecting said surfaces to fluid pressure for throwing said valve, and means provided by said bolt for admitting live pressure fluid alternately to said surfaces to accelerate the throwing action.

15. In a pressure fluid motor, a cylinder, a piston reciprocable therein, means forming distribution passages leading to said cylinder, a valve controlling said passages, buffers for limiting movement of said valve, a center bolt extending centrally through said valve for maintaining said buffers in assembled relation, said valve having opposed surfaces, means for alternately subjecting said surfaces to fluid pressure for throwing said valve, and means provided by said center bolt and controlled by said valve for admitting live pressure fluid alternately to said surfaces to accelerate the throwing action.

16. In a pressure fluid motor, a cylinder, a piston reciprocable therein, means forming distribution passages leading to said cylinder, a valve controlling said passages, means forming throwing passages for said valve, buffers for limiting movement of said valve, a center bolt extending centrally through said valve maintaining said buffers in assembled relation, and means provided by said center bolt and controlled by said valve for admitting live pressure fluid to one end of the latter prior to and for accelerating the throwing action thereon.

17. In a pressure fluid motor, a cylinder, a piston reciprocable therein, means forming distribution passages leading to said cylinder, a valve controlling said passages, means forming throwing passages for said valve, buffers for limiting movement of said valve, a center bolt extending centrally through said valve maintaining said buffers in assembled relation, means provided by said center bolt and controlled by said valve for admitting live pressure fluid to one end of the latter prior to the throwing action thereon, and means for venting the said end of said valve for preventing premature throwing thereof.

18. In a pressure fluid motor, a cylinder, a piston reciprocable therein, means forming distribution passages leading to said cylinder, a valve controlling said passages, means

for admitting live pressure fluid to the ends of said valve for throwing the latter, buffers for limiting movement of said valve, a center bolt extending centrally through said valve maintaining said buffers in assembled relation, means comprising passages formed in said bolt for admitting live pressure fluid to the ends of said valve and for venting the ends of the latter, and means including passages formed in said valve for alternately opening and closing said passages.

In testimony whereof I affix my signature,

THORE R. E. RUNDQVIST.
